UNITED STATES PATENT OFFICE.

HAROLD E. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

CIRCULAR-KNITTING MACHINE.

1,288,594.

Specification of Letters Patent. Patented Dec. 24, 1918.

Application filed March 5, 1918. Serial No. 220,436.

To all whom it may concern:

Be it known that I, HAROLD E. HOUSEMAN, a citizen of the United States, residing at Philadelphia, county of Philadelphia, and 5 State of Pennsylvania, have invented a new and useful Improvement in Circular-Knitting Machines, of which the following is a full, clear, and exact description, reference being had to the accompanying drawings, 10 which form a part of this specification.

My invention relates to independent needle cylinder knitting machines of that class which is adapted both to continuously rotate to form a circular knitted web and to oscillate to form the heel and toe pockets. Such machines are in general use for the manufacture of hosiery. My invention is of more especial advantage when applied to that 15 type of rotary-oscillatory machines wherein, 20 during the period of oscillation, only needles extending throughout one-half the circumference of the needles are in operative position and these needles are progressively thrown out of action, and then progressively 25 thrown into action, by means of pickers. The invention, however, is not limited in its application to the type of machine in which the needles are so operated by pickers, but is applicable to any circular machine which 30 is intended periodically to be given an oscillatory motion.

The object of the invention, in general, is to make possible an increase in the average speed of oscillation relatively to the speed 35 of rotation above that which has heretofore been deemed practicable and, as a means toward effecting this result, to vary the speed of oscillation along predetermined fractional parts of each oscillatory movement so as to 40 increase or decrease its speed, during such fractional parts of the movement, above or below the average speed of oscillation. The advantages of a machine having this capacity will be explained in connection with 45 the particular description of the accompanying drawings, wherein—

Figure 1 is a plan view, partly in diagram, of my improved motion-converting mechanism. Fig. 2 is an elevation of the same. 50 Fig. 3 is an enlarged horizontal section on the line 3—3 of Fig. 2. Fig. 4 is a vertical sectional view through the needle cylinder and appurtenant mechanism. Fig. 5 is a diagram on which are plotted the speed variations of different oscillatory motions. Fig.

6 is an enlarged diagram of a part of Fig. 5. Fig. 7 is a view, similar to Fig. 3, of a modification. Fig. 8 is an elevation of the mechanism shown in Fig. 7.

a is the frame of the machine and *b* the bed plate for the needle cylinder, cam ring and appurtenant mechanism. The needle cylinder *c* has secured to its lower end the driven gear *d* (which is actuated as herein-after described) resting directly upon the 65 ring *e* within the bed *b*.

The rotatable needle cylinder *c* is provided with vertical radial slots extending inward from its outer wall, the needles *f*, *g* extending within these slots and being movable upward therein to render them inactive, as is well understood in the art. Supported on the top of the bed plate is the cam ring *h* which carries the knitting cams for actuating the needles. 75

As is well understood, during the knitting of the leg of the stocking and during the knitting of that part of the stocking between the heel and toe, the needle cylinder is continuously rotating and all the needles are 80 down and in action. During the knitting of the heel and toe, the needle cylinder is oscillated and the needles *g* extending throughout one half the circumference of the needle bed, usually called the rear bank 85 of needles, are initially thrown out of action. This may be effected by providing the needles *g* with long butts and causing a cam to be moved into position to engage all the long butt needles and move them up out of 90 action. During the oscillation of the needle cylinder, the needles *f* extending throughout the remaining semi-circumference of the needle bed (that is, the front bank of needles) are thrown out of action one at a time, 95 first at one end of the semi-circumference and then at the other end, and so on alternately until only a limited number of needles in the central part of the front bank is in action. The needles are then thrown back 100 again into action one at a time in the reverse order in which they are thrown out. This operation is effected by means of "pickers", 20 and 21, one example of which may be found in the patent issued to Harry A. 105 Houseman, December 12, 1916, No. 1,207,757.

The above described mode of operation is typical of circular machines of the rotary needle cylinder type. All of them have a common serious disadvantage. The speed of os- 110

cillation must be reduced very much below the speed of rotation, thereby much increasing the time required to knit a complete stocking. If it is attempted to speed up 5 the machine during oscillation, the pickers will be rendered inoperative, it being impossible to devise any construction of pickers which will be operative if the speed of oscillation exceeds a maximum which is 10 recognized by the art and to which all machines are adapted. Specifically, it is found impracticable to maintain during oscillation a speed higher, relative to the highest practicable speed of rotation, than approximately 15 one to five; that is, one complete oscillation relative to five complete rotations. Of course, the ratio of oscillatory speed to rotary speed may be increased as desired by cutting down the absolute speed of rotation; 20 but this would be purposeless, as it would still further enlarge the time required to knit a complete stocking.

Heretofore, the art has converted the rotary movement of the main driving shaft 25 into an oscillatory movement of the needle cylinder by means of driving connections including a crank. As an example of such a construction, reference may be made to the Houseman patent hereinbefore mentioned.

30 It is well known to mathematicians and to mechanical engineers that when a movement of rotation is converted into a movement of oscillation, the part oscillated has a certain speed which has a certain constant 35 variation. Generally speaking, this speed is zero at the dead center of the crank, then increases until it reaches its maximum, and then slows down until it again reaches zero at the opposite dead center of the crank. 40 The relative speed, near the beginning of each oscillation, is extremely slow, but thereafter very rapidly increases until it approaches, but does not quite reach, its maximum upon the completion of (say) one- 45 sixth of its stroke. It will be understood that in a knitting machine the needle cylinder has precisely the differential speed above described. Bearing in mind that the pickers operate upon the needles during the first 50 third of each stroke of oscillation or reciprocation, it will be understood that during the latter part of the operation of the pickers, they are operating the butts of needles which are moving close to their maximum 55 circumferential speed.

The condition may be more clearly understood by reference to the diagram, Fig. 5, reference being made first to the dotted line x , as distinguished from the broken line y and 60 the solid line z . The horizontal base line represents the time elapsing during a number of complete rotations of the needle cylinder, the Figs. 1, 2, 3, 4 and 5 representing the number of rotations. Each unit is 65 conveniently divided into eighths, and from the

points of division are projected vertical lines. The dotted line x is a curve plotted to show the variation in speed of a crank-oscillated member on the assumption that the machine is geared one to four; that is, one 70 complete oscillation to four complete rotations. The relative speed of oscillation during each period of time required to make one eighth of one complete rotation is represented by the vertical distance between the 75 two points where the line x intersects two adjacent vertical lines. It will be observed that during the time required to make the first eighth of the first rotation, the speed of oscillation is little more than zero, but that, 80 after the time required to make (say) one-half a rotation has elapsed, and the oscillating member has moved little more than one-sixth of its stroke, the speed of oscillation is already closely approaching its maximum and has already become so great as to be beyond that allowable for safe operation of the pickers. As will be observed from the drawings, the pickers do not complete their operation until the completion of 90 about one-third of a stroke, w indicating the picker safety line below which a certain speed must not be exceeded.

When, however, the ratio of oscillation is reduced to one to five, the travel of the oscillatory member is represented by the curved broken line y . It will be observed, by reference to the diagram, that not only is the average speed of travel of the oscillatory member reduced, but the approach toward maximum 100 speed is more slow and that its speed is no greater, after it has completed about one-third of its stroke, than its speed, when geared one to four, after it had completed little more than one-sixth of its stroke. It 105 will be thus understood why the pickers will operate with certainty and safety when the speed of oscillation relatively to the speed of rotation is one to five, whereas their safe and certain operation cannot be secured 110 with a relative speed of one to four.

The specific object of my invention is to increase the average speed of oscillation while so limiting the speed in that part of the movement during which the pickers are 115 operative as to enable the pickers to perform their function with safety and certainty. It is clear, from the foregoing explanation, that this cannot be done so long as the oscillatory motion of the needle cylinder is effected by means of a crank and I have therefore abandoned the crank as a part of the power transmitting means and have substituted other power transmitting means, as will 120 hereinafter be particularly described.

The gear d , which, as hereinbefore described, is secured to the needle cylinder, is driven through idler i from gear j on the clutch shaft. Feathered on the clutch shaft is a clutch o which, by appropriate auto- 130

matically operating means (not herein shown) may be shifted into engagement with either a constantly rotating pinion m or a constantly oscillating pinion n , both 5 loose on the clutch shaft. Pinion m is constantly rotated by being continually in mesh with a spur gear q secured to a rotating shaft r . Attached to gear q is a bevel gear s which is driven by a bevel pinion t on a 10 driving shaft u . As far as thus described, the construction is not essentially different from what is old and well known, but the following novel mechanism is employed to impart a movement of oscillation to the 15 pinion n .

Carried by the shaft r is a double cam composed of the cam members 10 and 11. Loose on a shaft 12 is a hub 13 secured to which is a reciprocating or rocking frame 20 composed of two arms 14 and 15 provided respectively with rollers 16 and 17 engaging respectively the peripheries of cams 10 and 11. The arm 14 of the rocking frame carries a curved rack or segmental gear 18, 25 which meshes with the pinion n .

In the embodiment of my invention herein shown, the parts are so proportioned that when the needle cylinder is driven from the rotary pinion m it will be given four complete rotations in the same time that it is oscillated back and forth when driven from the oscillatory pinion n . Further, the cams 30 10 and 11 are so shaped that at each oscillatory stroke of the needle cylinder, it will 35 pick up speed rather rapidly and maintain, for about one-third the length of its stroke, a speed substantially less than the average speed and a speed sufficiently low to permit the pickers to operate with certainty and 40 safety, after which the speed is maintained above the average and at its maximum until the oscillatory stroke is nearly completed, there being then a rapid drop in the speed until it reaches zero at the end of the stroke. 45 This operation is illustrated by the full line z in Figs. 5 and 6. It will be observed that, in each oscillatory stroke, the speed picks up more rapidly than in a four to one crank motion, as represented by the line w , but that 50 the speed soon drops behind the crank motion speed and is maintained behind until after the line rises above the "picker safety line" w , after which the speed is increased to its maximum and is maintained at its 55 maximum until near the end of its stroke. The lines w and z have the same comparative characteristics in their downward bends, which represent the return stroke in the oscillation of the needle cylinder, v representing the "picker safety line" on this 60 stroke. It will also be observed that the maximum speed represented by the line z below the picker safety line w in the advance stroke of oscillation is actually less 65 than the maximum speed below that line

represented by the line y , although the line y represents a slower average speed, as hereinbefore described.

The drawing illustrates with approximate accuracy the shape of the cams 10 and 11 70 that will produce a variable speed of oscillation corresponding to that indicated by the line z ; but any skilled engineer may plot the curve of his speed line to suit the conditions of his particular machine and then lay 75 out his cams accordingly; the advantage of my construction being that the designer is not limited to the precise speed variations imposed by a crank motion.

It will be clear, from the foregoing description, that, by a limited reconstruction, in accordance with my invention, of the driving mechanism of any rotary-oscillatory circular knitting machine, the average speed of oscillation relative to the speed of rotation may be increased while at the same time the maximum speed of movement of the needles while the pickers are in operation will not be increased, but may actually be decreased so as to increase the working margin 80 of safety. It is clear that the time required to knit a complete stocking may thus be materially reduced and the capacity of the machine thereby be materially increased.

While I have illustrated mechanism proportioned to drive the needle cylinder so that it will oscillate back and forth once in the time required for four complete rotations, the invention is of course not limited to this particular ratio, it being clear that 95 the ratio of oscillation to rotation, as well as the speed variation above and below the predetermined average, depends upon the proportioning of the driving elements and the shape of the cams, which are within 100 the range of mechanical skill. Thus, it is practicable, although much less desirable, to so shape the cam that in the oscillation of the needle cylinder it will speed up, as it leaves its dead center, very suddenly, and 105 will slow down, as it approaches its dead center, very suddenly. Thereby it is possible, with a given ratio of rotation to oscillation, to reduce the speed of the needle cylinder, during the operation of the pickers, somewhat below that which it would have if actuated by a crank motion. The wear and tear on the driving and driven parts would be such, however, in this modification, due to sudden changes of speed, as 110 to make it comparatively undesirable, although it represents one of the possibilities of my invention.

I have so shaped the cam face of the cam members, 10 and 11, that when either cam 125 member is positively actuating its corresponding roller 16 or 17, the other roller is hugging the cam face of the other cam member, thereby insuring the smooth operation of the mechanism and, in particular, pre- 130

venting the rocking frame 14—15 jumping forward, by the momentum of the driven parts, during the slowing down movement, as would be the case if it were not restrained 5 from so doing by the cam member which, at the time, was not actually driving. Where, therefore, in the claims, I specify a "cam" without qualification, I mean to include either the preferred double cam 10—11 or the single cam 100, or any mechanical equivalent.

While I prefer to use a double cam, such, for example, as has been described, it is not impracticable to employ a single cam, one 15 example of which is shown in Figs. 7 and 8, wherein 100 represents the actuating cam, 140 the reciprocating frame, 160 and 170 rollers carried by the frame and actuated by the cam 100, 180 the rack carried by the 20 frame and n' the driven pinion corresponding to the pinion n . 21, 21, are guides fixed on the frame of the machine, in which slide the ends of the frame 140.

While the part c is designated the needle cylinder, it is obvious that the invention is 25 applicable to that type of circular knitting machine wherein the needle cylinder is stationary and the cam ring or cylinder rotates. In such machines, so far as concerns 30 my invention, the cam ring or cylinder would be the equivalent of the needle cylinder of the rotary needle cylinder type.

Having now fully described my invention, what I claim and desire to protect by 35 Letters Patent is:

1. In a circular knitting machine, in combination, a needle cylinder turnable on its axis, rotary driving means, driven means operatively connected with the needle cylinder, and connections between the driving means and the driven means adapted to convert the rotary movement of the former into an oscillatory movement of the latter, said motion-converting connections comprising a cam the shape of whose operative face determines the variation in the speed 40 of oscillation.

2. In a circular knitting machine, in combination, a needle cylinder turnable on its 50 axis, rotary driving means, oscillatory driven means, rotary driven means, clutch shifting mechanism whereby either of said driven means may be operatively connected with the needle cylinder, and driving connections between the driving means and the oscillatory driven means, said driving connections comprising a cam the shape of whose operative face determines the variation in the speed of oscillation.

3. In a circular knitting machine, in combination, a needle cylinder turnable on its axis, rotary driving means, driven means operatively connected with the needle cylinder, and connections between the driving 60 means and the driven means adapted to

convert the rotary movement of the former into an oscillatory movement of the latter, said motion-converting connections comprising a cam having an operative face shaped to impart to the driven means a 70 relatively slow movement throughout the first and shorter part of each stroke and a relatively rapid movement during most of the remaining and longer part of each stroke, whereby the average speed of oscillation 75 may be maintained relatively high while maintaining a relatively slow speed throughout that part of the period of oscillation during which the needles are progressively rendered active and inactive. 80

4. In a circular knitting machine, in combination, a needle cylinder turnable on its axis, rotary driving means, oscillatory driven means, rotary driven means, clutch shifting mechanism whereby either of said 85 driven means may be operatively connected with the needle cylinder, and driving connections between the driving means and the oscillatory driven means, said driving connections comprising a cam having an operative face shaped to impart to the oscillatory driven means a relatively slow movement during the first and shorter part of each stroke and a relatively rapid movement during most of the remaining and longer part 90 of each stroke, whereby the speed of oscillation may be maintained relatively slow while the needles are being progressively rendered active and inactive while maintaining a high average speed of oscillation. 100

5. In a circular knitting machine, in combination, a needle cylinder turnable on its axis, rotary driving means, driven means operatively connected with the needle cylinder, and connections between the driving 105 means and the driven means adapted to convert the rotary movement of the former into an oscillatory movement of the latter, said motion-converting connections comprising mechanism to impart to the driven means 110 an oscillatory motion analogous to that of a crank but characterized by a relatively slower movement during the larger part of the first and shorter part of a stroke.

6. In a circular knitting machine, in combination, a needle cylinder turnable on its axis, rotary driving means, oscillatory driven means, rotary driven means, clutch shifting mechanism whereby either of said 115 driven means may be operatively connected with the needle cylinder, and driving connections between the driving means and the oscillatory driven means, said driving connections comprising mechanism to impart to the oscillatory driven means an oscillatory motion analogous to that of a crank but characterized by a relatively slower movement during the larger part of a first and shorter part of a stroke. 120

7. In a circular knitting machine, in com- 125

- bination, a needle cylinder turnable on its axis, rotary driving means, driven means operatively connected with the needle cylinder, and connections between the driving 5 means and the driven means adapted to convert the rotary movement of the former into an oscillatory movement of the latter, said motion-converting connections comprising a reciprocating frame and a rotary cam 10 operating the frame and shaped to determine the variation in speed of oscillation of the driven means.
8. In a circular knitting machine, in combination, a needle cylinder turnable on its axis, rotary driving means, oscillatory driven means, rotary driven means, clutch shifting mechanism whereby either of said driven means may be operatively connected with the needle cylinder, and driving 15 connections between the driving means and the oscillatory driven means, said driving connections comprising a reciprocating frame and a rotary cam operating the frame and shaped to determine the variation in speed 20 of oscillation of the oscillatory driven means.
9. In a circular knitting machine, in combination, a needle cylinder turnable on its axis, rotary driving means, driven means operatively connected with the needle cylinder, and connections between the driving 25 means and the driven means adapted to convert the rotary movement of the former into an oscillatory movement of the latter, said motion-converting connections comprising a cam composed of two rotary members and a reciprocating frame and means carried thereby engaging the respective actuating faces of the two cam members and co-operating therewith to determine the variation in 30 the speed of oscillation of the driven means.
10. In a circular knitting machine, in combination, a needle cylinder turnable on its axis, rotary driving means, oscillatory driven means, rotary driven means, clutch shifting mechanism whereby either of said driven means may be operatively connected with the needle cylinder, and driving 35 connections between the driving means and the oscillatory driven means, said driving connections comprising a cam composed of two rotary members and a reciprocating frame and means carried thereby engaging the respective actuating faces of the two cam members and co-operating therewith to determine the variation in 40 the speed of oscillation of the driven means.
11. In a circular knitting machine, in combination, a needle cylinder turnable on its axis, a shaft, driving connections between 45 the shaft and the needle cylinder, a rotary pinion and an oscillatory pinion on the shaft, clutch shifting mechanism whereby said shaft may be operatively connected with either pinion, a rotary driving shaft, driving connections therefrom to the rotary pinion, 50 a cam the shape of whose operative face determines the variation in the speed of the oscillatory pinion.
12. In a circular knitting machine, in combination, a needle cylinder turnable on its axis, a shaft, driving connections between the shaft and the needle cylinder, a rotary pinion and an oscillatory pinion on the shaft, clutch shifting mechanism whereby said shaft may be operatively connected with either pinion, a rotary driving shaft, driving 55 connections therefrom to the rotary pinion, a cam composed of two members and rotatable from the driving shaft, a reciprocating frame geared to the oscillatory pinion, and means carried by the reciprocating frame 60 engaging the respective actuating faces of the two cam members.
13. In a circular knitting machine, in combination, a needle cylinder adapted to be oscillated on its axis, independently operable needles carried by said cylinder, pickers adapted to move said needles into and out of operation during the first part of an oscillatory stroke, rotary driving means, 65 driven means operatively connected with the needle cylinder, and motion-converting driving connections between the rotary driving means and said driven means adapted to oscillate the latter at a relatively slow speed 70 throughout that part of each stroke during which said pickers are so actuating the needles and at a relatively high speed during most of the remaining and longer part of each stroke, whereby the average speed of 75 oscillation may be maintained relatively high while providing for the safe and certain operation of the pickers.
14. In a circular knitting machine, in combination, a needle cylinder turnable on its axis, a rotary driving means, driven means operatively connected with the needle cylinder, and connections between the driving means and the driven means adapted to convert the rotary movement of the former into 80 an oscillatory movement of the latter, said motion-converting connections comprising a rotary cam actuated by the driving means and a reciprocating frame actuated by the cam, said frame comprising two parts one 85 of which is being positively actuated by the cam while the other is simultaneously maintained in close relationship to the cam, whereby the driven means is operated at a predetermined variable speed and restrained 90 from any movement independent of its driving means.
15. In a circular knitting machine, in combination, a needle cylinder turnable on its axis, rotary driving means, oscillatory 95

- 6
- driven means, rotary driven means, clutch shifting mechanism whereby either of said driven means may be operatively connected with the needle cylinder, and driving connections between the driving means and the oscillatory driven means, said driving connections comprising a rotary cam actuated by the driving means and a reciprocating frame actuated by the cam, said frame comprising two parts one of which is being positively actuated by the cam while the other is simultaneously maintained in close relationship to the cam, whereby the oscillatory driven means is operated at a predetermined variable speed and restrained from any movement independent of its driving means.
16. In a circular knitting machine, in combination, a needle cylinder turnable on its axis, rotary driving means, driven means operatively connected with the needle cylinder, connections between the driving means

and the driven means adapted to convert the rotary movement of the former into an oscillatory movement of the latter, an oscillating frame pivoted at one end and engaging an element of the driven means at its other end, two rotary cam members turnable by the driving means on an axis located between the pivot of the frame and said element of the driven means, and means carried by the frame engaging the respective actuating faces of the two cam members so as to be swung in one direction by one cam member and in the other direction by the other cam member and restrained from independent movement at any time by the cam member whose driving function is at such time interrupted.

In testimony of which invention, I have hereunto set my hand, at Philadelphia, Pa., on this 25th day of February, 1918.

HAROLD E. HOUSEMAN.
